UNITED STATES PATENT OFFICE.

JOSEPH H. SHEARD, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

STOREROOM FURNITURE.

Application filed May 12, 1928. Serial No. 277,288.

This invention relates to furniture or fixtures such as shelving, cabinets, etc., for store or stock rooms, or in other words, to structures providing a multiplicity of individual

5 compartments or bins to accommodate as many different varieties of articles. For use in certain industries it is requisite that the furniture of the kind referred to be re-arrangeable so that the sub-divisions, i. e., the 10 compartments or bins may be changed in number and capacity at will. One outstanding instance where this consideration is of prime importance is with furniture suitable for store rooms of automobile service establishments where a great number of parts must 15 always be carried in stock, and where allowance must be made for recurrent variations in the numbers and sizes of the stored parts brought about by changes in yearly models 20 of the automobiles. Furniture for uses such as exemplified is accordingly constructed with partitioning units capable of re-arrangement in accordance with the dictates of practice. With employment of ordinary screw bolts 25 and nuts, as was usually the case heretofore, to detachably secure the partition units in place, re-arrangement of the latter was very laborious and, moreover, consumed a great deal of time as well as being costly.

30 My invention is directed toward overcoming the drawbacks just pointed out. This desideratum I attain, as hereinafter fully described, through provisions whereby the re-arrangeable partitioning of the furniture is detachably held in place through interaction of the parts themselves thereby dispensing with the necessity for separate securing devices and the use of special tools in making the changes.

35 With reference to the drawings Fig. I is a partial front elevation of a storage structure conveniently embodying my invention.

Fig. II is a perspective view of one of the shelves comprised in the structure.

40 Fig. III is a detail section at the region III in Fig. I, but drawn to a larger scale.

Fig. IV is a perspective view of a dividing partition used in conjunction with the shelves to set apart individual compartments or sub-divisions in the structure.

45 Fig. V is a view, similar to Fig. I, showing an alternative embodiment of my invention.

Fig. VI is a sectional view through one of

the shelves of the modification, taken as indicated by the arrows VI—VI in Fig. V, and 55

Fig. VII shows one of the shelves in perspective.

In Fig. I of these illustrations my improved store room structure is delineated as embodying a frame 9 of sheet metal with end walls 10 and top 11 to support a number of shelves 12. Each of these shelves 12 is fashioned in the present instance, from a single piece of sheet metal with the edges bent at right angles to form stiffening flanges 13, 14, 15 and 16 all around, see Fig. II. The end flanges 14, 16 are provided with holes 17 for selective registry with vertically arranged apertures 18 in the end walls 10 of the frame 9—Fig. I—and to take securing devices 19. Obviously 70 with the described arrangement, the shelves 12 may be placed at different levels as desired or required in suiting the structure to diversified uses in practice. The frontal flanges 13 of the shelves may be turned over at the top 75 with formation of retroversions 13x constituting jointly with similar counter retroversions of attached strips 20, holders for identification cards or the like not shown.

To enable further subdivision of the structure, I provide partitions 21 also of sheet metal with oppositely-disposed offsets 22, 23 along their upper and lower edges adapted to engage opposing recesses afforded by vertically-aligned pairs of transverse hook-like or 80 S-section corrugations 24 at uniformly-spaced intervals along the shelves 12. In the illustrations, the corrugations 24 are shown as curved and have their component reverse convolutions symmetrically disposed above 90 and below the body plane of the sheet material from which the shelves are made; while the offsets 22, 23 of the dividing partitions are curled to the form of rounded beads with the curvature corresponding to that of the 95 troughs or recesses of said corrugations. It is of course to be understood that the corrugations 24 of the shelves 12 and the interfitting offsets or beads 22, 23 of the partitions 21 may be made angular or configured 100 otherwise than shown providing their component halves are respectively disposed above and below the body plane of the shelf, as above set forth. By virtue of construction from sheet metal the partitions 21 can 105 be readily sprung into place, for example, by

engaging the lower bead 23 in a selected recess in a bottom shelf 12, as suggested in dotted lines in Fig. III, and then applying sidewise pressure to flex the metal until the 5 upper bead 22 snaps into place in the opposing recess of the super-adjacent shelf 12. Preferably the inner vertical edge of the dividing partitions 21 are flanged as at 25 in Fig. IV for greater rigidity, and the outer 10 edges rolled as at 26 to present a neater finish and to improve the general appearance and strength of the whole structure. In practice the dividing partitions 21 are made available in different heights to suit various vertical 15 spacing of the shelves 12.

Referring now to the alternative embodiment of my invention shown in Figs. V-VII let it be assumed that the frame 9a is identical in construction and design with 20 the frame 9 previously described. The shelves 12a of the modification are however composite in construction, that is to say: they are formed with a single piece bottom 30 having double corrugations 24a spaced as 25 before, but in this instance, extending the full width of said shelves, the metal being turned up at opposite ends to afford attaching flanges 14a, 16a. The rear flanges 15a are provided by angle rails 31 Fig. VI which may 30 be permanently secured to the tray bottoms 30 by riveting, welding, or in any other convenient manner, and have their horizontal legs directed inwardly beneath the bottom 30 to assist in its support. As in the first 35 instance, the flanges 14a, 16a are pierced as at 17a for selective registry with apertures 18a in the end walls 10a of the frame 9 and to take securing devices 19a. The frontal or retaining flanges 13a are provided by angle 40 rails 32, which, like the rails 31, may be either permanently secured to the shelves 12a, or detachably secured by any suitable means with capacity for ready removal to permit the dividing partitions 21a to be slid endwise 45 into engagement with the opposing recesses of vertically-aligned double corrugations 24a in adjacent shelves 12a instead of being sprung into place as described in connection with the first embodiment. All elements of 50 the modification not specifically described but having their counterparts in Figs. I-IV are identified with the same reference numerals previously employed except for addition of distinguishing suffixes, the necessity 55 for duplicity of description being accordingly avoided.

Having thus described my invention, I claim:

1. A storage structure of the character described comprising shelves with transversely-extending hook-section corrugations, the component halves of said corrugations being disposed above and below the body plane of the shelves, and positionally rearrangeable vertical dividing partitions of flexible material

capable of being sprung into place with their upper and lower edges engaging opposing recesses in adjacent shelves.

2. A storage structure of the character described having shelves with transversely-extending hook-section corrugations at intervals, the component halves of said corrugations being disposed above and below the body plane of the shelves, and positionally rearrangeable vertical dividing partitions of sheet material capable of being sprung into place with their upper and lower edges engaging opposing recesses afforded by the corrugations in adjacent shelves. 75

3. A storage structure of the character described having shelves with transversely-extending substantially S-section corrugations at spaced intervals, the component faces of said corrugations being disposed above and below the body plane of the shelves, and vertical dividing partitions of sheet material capable of being sprung into place with rounded beads along their upper and lower edges engaging in opposing curved recesses afforded by the corrugations in adjacent shelves. 80

4. A storage structure of the character described having shelves with transversely-extending substantially S-section corrugations at uniformly-spaced intervals, the component halves of said corrugations being disposed above and below the body plane of the shelves, and dividing partitions with their upper and lower edges offset in opposite directions to engage opposing recesses afforded by vertically co-ordinated double corrugations of adjacent shelves. 95

5. A storage structure of the character described having shelves with transversely-extending substantially S-section corrugations at uniformly-spaced intervals, the component halves of said corrugations being disposed above and below the body plane of the shelves, and vertical dividing partitions formed from sheet material with oppositely directed rounded beads along their upper and lower edges to engage opposing curved recesses of vertically co-ordinated corrugations of adjacent shelves. 100

6. A storage structure of the character described comprising shelves having, at spaced intervals, transversely extending substantially S-section corrugations, the component halves of such corrugations being oppositely disposed above and below the body plane of the shelves, and vertical dividing partitions with their upper and lower edges offset in opposite directions to engage opposing recesses afforded by vertically co-ordinated corrugations in adjacent shelves. 110

7. A storage structure of the character described comprising shelves having bottoms formed from sheet material to embody uniformly-spaced substantially S-section transverse corrugations with the ends bent per-

pendicularly for service as attaching flanges, and with complementary front and rear flanges provided by separately attached angle rails, the component halves of said corrugations being disposed above and below the body plane of the shelves, vertical dividing partitions held in position through engagement of their upper and lower edges in opposing recesses afforded by the corrugations of adjacent shelves; and vertical dividing partitions held in position through engagement of their upper and lower edges in opposing recesses afforded by the co-ordinated corrugations of adjacent shelves.

8. A storage structure of the character described comprising shelves having bottoms formed from sheet material to embody uniformly-spaced substantially S-section transverse corrugations with the ends bent perpen-

dicularly for service as attaching flanges, the component halves of said corrugations being disposed above and below the body plane of the shelves, vertical dividing partitions held in position through engagement of their upper and lower reversely curled edges in opposing recesses afforded by the corrugations of adjacent shelves, and retaining flange rails along the fronts of the shelves capable of detachment therefrom to facilitate removal or rearrangement of the dividing partitions.

In testimony whereof, I have hereunto signed my name at Philadelphia, Pennsylvania, this 5 day of May, 1928.

JOSEPH H. SHEARD.
